UNITED STATES PATENT OFFICE

ARTHUR H. MOTT, JR., OF DETROIT, MICHIGAN

CIRCUIT CLOSER

Application filed January 17, 1930. Serial No. 421,461.

This invention relates to improvements in vehicle direction signals and has especial relation to means for controlling the operation of the signal.

An object of the present invention is the provision of an automobile signal which may be set to indicate a right or left turn, and which will be automatically restored to normal position at the completion of the turn, or may be manually reset prior to or without making the turn.

With the above and other objects in view, the invention further includes the following novel features and details of construction, to be hereinafter more fully described, illustrated in the accompanying drawings and pointed out in the appended claims.

In the drawings:—

Figure 1 is a plan view of the controlling switch showing a fragmentary portion of a steering wheel to which it is applied.

Figure 2 is a section on the line 2—2 of Figure 1.

Figure 3 is a fragmentary plan view showing the contact strips and the insulated housing therefor.

Figures 4 and 5 are fragmentary sectional views taken respectively on the lines 4—4 and 5—5 of Figure 3.

Figure 6 is a horizontal sectional view illustrating the switch unit.

Figure 7 is a section on the line 7—7 of Figure 6.

Figure 8 is an inner plan view showing the switch unit.

The mechanism mentioned comprises an annular relatively shallow transversely channel-shaped housing 22. This housing is formed of insulating material and has embedded therein spaced concentrically arranged annular contact strips 23, 24 and 25. The strip 23 is adapted to be connected in circuit with a left turn signal device, while the strip 25 is adapted to be connected in circuit with a right turn signal device, the strip 24 being connected with a battery or other source of current and with each of the lamps. Thus, the lamps are included in open circuits and when the strips 23 and 24 are bridged, a circuit will be completed through the left

signal device 21 to indicate a left turn, and when the strips 24 and 25 are bridged a circuit will be completed through the right signal device 20 and a right turn indicated.

The housing 22 which, as previously stated, is transversely channel-shaped, is provided around its edges with seats 26. These seats receive the opposite edges of an annular insulated cover 27 which is held for sliding rotary movement by means of narrow retaining bands 28.

The cover 27 is provided with an offset portion 29 which forms a housing for a switch unit, and this housing is secured to the steering wheel 30 of an automobile through the medium of an attaching plate 31 and screws 32. By this means when the steering wheel is rotated, the cover 27 will be rotated within the seat 26 of the housing.

Secured within the offset portion 29 of the cover is a plate 33, the latter being held in place by screws 34, and by hollow bolts 35. Mounted for rotation in bushings 36 carried by the plate 33 are posts 37 and 38, the former having fast thereon a wing 39 and the latter having fast thereon a wing 40. Secured to the opposite ends of the posts 37 and 38 respectively are resilient contact arms L and R. These arms are normally spaced between the strips 23, 24 and 25, but the arm L when rotated to a position at right angles to that shown by dotted lines in Figure 6, will bridge the strips 23 and 24 and complete a circuit through a lamp to indicate a left turn. Likewise, when the arm R is moved to bridge the contacts 24 and 25, a lamp will be illuminated and a right turn indicated.

In order to move the arm R to an active position, the offset portion 29 of the cover 27 is provided with a bushing 41, and slidably through this bushing is a plunger rod 42. The inner end of this rod is provided with an offset foot 43 which is adapted to engage the wing 40, and when the plunger rod 42 is depressed, to move this wing from the dotted to the full line position shown in Figure 6, whereupon the contact arm R will bridge the contacts 24 and 25 as previously stated. The arm R is yieldingly held in an active or inactive position by means of a

spring 44, as shown in Figure 6 of the drawings. A spring 45 which is mounted upon the plunger rod 42 beneath an operating button 46 acts to return the plunger rod 42 to its normal position.

The hollow bolts 35 provide bearings for plunger rods 47 and 48. These rods are provided with operating buttons 49 and 50 respectively and are yieldingly forced outward by means of springs 51. The inner end of the plunger rod 47 carries branch arms 52 and 53, the arm 52 forming a stop for the wing 40 and limiting pivotal movement of the contact arm R in one direction. In addition, by pushing the plunger rod 47 inward, the wing 40 will be moved to move the spring 44 past the center and restore the contact arm R to its normally inactive position. In this position, the wing 40 engages the foot 43 so that movement of the contact arm 40 is limited in this direction.

The plunger rod 48 is arranged in the path of movement of the wing 39 in one direction and acts as a stop to hold the contact arm L in neutral position. Also, the plunger rod 48 is adapted to be pushed inward to move the wing 39 and the contact arm L into position to bridge the strips 23 and 24, movement in this direction being limited by the arm 53 on the plunger 47. Thus, the plunger 47 may be operated to return either the arm R or the arm L to neutral position independently or simultaneously. Stop pins 54 limit outward movement of the plunger rods.

When it is desired to indicate a right turn, the right turn button 46 is pushed inward so that the contact arm R will bridge the contacts 24 and 25 as previously explained. The steering wheel is then operated in a clockwise direction and carries with it the switch unit, the right signal device being illuminated as soon as the button 46 is operated. During this operation, one end of the contact arm R will ride over a tooth 55 which extends upward from the strip 25, so that when the turn is completed and the steering wheel straightened out, the arm R will be in a neutral position between the strips 24 and 25.

Likewise, when the steering wheel is moved in an anti-clockwise direction to make a left turn, the left signal device will be illuminated. During this movement of the steering wheel, the contact arm L will ride over a tooth 56 which extends upward from the strip 23, reverse movement of the steering wheel causing the arm L to engage this tooth, whereupon the arm will be returned to its normally inactive position.

The invention is susceptible of various changes in its form, proportions and minor details of construction and the right is herein reserved to make such changes as properly fall within the scope of the appended claims.

Having described the invention what is claimed is:—

1. In an automobile signal controlling switch, a plurality of spaced stationary contact strips adapted to be connected in circuit with a signal device, a relatively movable switch unit adapted to be secured to the steering wheel of an automobile, normally inactive independently movable contacts included in the movable switch unit, means to selectively move the contacts to bridge two of the contact strips and complete a circuit, spaced means arranged in the path of the movable contacts to restore the latter to inactive position, and manually operated means to restore said movable contacts to inactive position. 75 80

2. In an automobile signal switch, a stationary unit, a movable unit slidably associated therewith and adapted to be attached to the steering wheel of an automobile for movement therewith, said movable unit including pivotally mounted normally inactive contact arms, contacts carried by the stationary unit for engagement by said arms, a plunger for each contact arm to move said arms from an active to an inactive position, and means to restore one or both of the pivotally mounted contact arms to an inactive position. 85 90

3. In an automobile signal switch, a stationary unit, a movable unit slidably associated therewith and adapted to be attached to the steering wheel of an automobile for movement therewith, said movable unit including pivotally mounted normally inactive contact arms, contacts carried by the stationary unit for engagement by said arms, a plunger for each contact arm to move said arms from an active to an inactive position, and a plunger common to both of the pivotally mounted contact arms to restore the latter to an inactive position. 95 100 105
